UNITED STATES PATENT OFFICE

REUBEN BALL THOMPSON, OF STILLWATER, NEW YORK, ASSIGNOR TO WILLCOX & GIBBS SEWING MACHINE COMPANY, OF NEW YORK, N. Y., A CORPORATION OF NEW YORK

FEEDING MECHANISM FOR SEWING MACHINES

Application filed August 6, 1928. Serial No. 297,767.

This invention relates to feeding mechanism for sewing machines, and has for its particular object the provision of improved means for adjusting the length of feeding movement or throw of one of the four-motion feed dogs of differential feed mechanisms.

What is now believed to be the preferred embodiment of the invention is illustrated in the accompanying drawings as applied to the well known "Overlock" sewing machine of the Willcox & Gibbs Sewing Machine Company. In said drawings:

Fig. 1 is a side elevation partly in section; Fig. 2 is a side elevation of the feeding mechanism detached from the casing and other parts shown in Fig. 1;

Fig. 3 is a top view of the parts shown in Fig. 2;

Fig. 4 is an end view looking from the left of Fig. 2;

Fig. 5 is an elevation of the feed rocker detached from the other parts illustrated in connection therewith in Fig. 4;

Fig. 6 is an elevation of the feed rocker viewed from the side opposite to that from which Fig. 5 is taken;

Fig. 7 is a horizontal section on line 7—7 of Fig. 4;

Fig. 8 is an elevation of the rear feed dog and its feed bar and the feed rocker (partly in section) by which said bar is actuated;

Fig. 9 is a similar view of the front feed dog and its feed bar and the feed rocker;

Fig. 10 is a vertical section on lines 10—10 of Figs. 3, 4 and 7, but including part of the casing which is not shown in said views;

Fig. 11 is a detail view showing the adjusting screw and associated parts;

Figs. 12, 13, 14 and 15 are more detail views of individual parts.

Referring to the parts by reference numerals, 20 is the bed-plate constituting the cover of a box casing parts of which are shown at 21 in Figs. 1 and 10. 22 is a presser-foot carried by presser-foot bar 23; 24 is a needle carried by a needle bar; 25 is a vertically operating trimmer blade; 26 is an up-standing deflector, guard or guide-plate; and 27 is a front feed-dog (or feed surface) and 28 is a rear feed dog, both dogs working

through an opening 29 in the bed plate 20 in engaging and feeding fabric, such as shown at 30, Fig. 1. All of these parts are the same as in said commercial Overlock machine.

The feed dogs 27 and 28 are secured to the forward ends of feed bars 35 and 36, respectively, as best shown in Figs. 8 and 9; and each bar is formed with a slideway along its under edge. As shown in Fig. 2 with reference to feed bar 35, a pair of blocks 37 work in said slideway of each bar and an eccentric 38 on shaft 39 works in a circular opening formed between each pair of blocks. By this arrangement rotation of shaft 39 and eccentric 38 thereon imparts up and down movement (of the well known four-motion feed movement) to the feed bars and to the feed dogs carried thereby, all in well-known manner.

A feed rocker, best shown in Figs. 4, 5 and 6, comprises two upstanding parallel arms 40 and 41 connected at their lower ends by a base portion 42, the whole forming a U-shape construction but with the arm 40 shorter than arm 41. The feed rocker fulcrums on stud axles 43 and 44 projecting from opposite ends of the rocker, the stud 44 engaging an opening in the lower end of a bracket arm 45 depending from the under side of bed plate 20, as shown in Fig. 1, and the stud 43 engaging an opening in a similar bracket arm not shown.

As shown in Fig. 1, rocking movement is imparted to the feed rocker from shaft 39 by means of eccentric 46 on said shaft actuating a bar 47 which is adjustably connected with the feed rocker by means of a pivot stud 48 adjustable in a slot 49 in a vertical flange 50 on the long arm 41 of the feed rocker. The scale of numbers "12", "14", "16", etc., appearing in Figs. 1 and 2 on the flange 50 along the slot 49, indicates the number of stitches per inch for different positions of adjustment of pivot stud 48.

The rear end of feed bar 36 is connected to the upper end of the short arm 40 of the feed rocker by a pivot pin 55. The feed bar 35, of the front feed dog 27, is supported near its rear end from the feed bar 36 by a shouldered stud screw 60 secured to bar 36.

and making sliding engagement in a horizontal slot or guideway 61 in bar 35, whereby the bars may move relatively to each other longitudinally. The rear end of feed bar 35 is connected to the feed rocker by a pivotal connection such as to be easily and accessibly adjustable thereby to vary the length of feeding movement imparted to said feed bar 35 and to the feed dog 27 carried thereby. At its said rear end, feed bar 35 has a downward approximately vertical extension 35^a, having therein an upright slot or guideway 62. A feed adjusting slide shoe 63 (best shown in Figs. 7, 9 and 14) is adjustably movable in said slot 62 and said shoe 63 has an opening engaged by a pivot stud 64 at one end of a feed adjusting slide 65 which has at its other end a rib or projection 66 making sliding engagement in an upright groove or guideway 67 in the inner face of arm 41 of the feed rocker—all as shown in Figs. 4, 5 and 13.

A feed adjusting screw 70 engages through an interiorly screw-threaded opening in slide 65, whereby rotation of said screw adjusts the position of said slide and thereby moves the pivot stud 64 thereon either closer to the axis (of studs 43 and 44) on which the rocker oscillates—to thereby shorten the feeding movement imparted to feed bar 35 and its feed dog 27, or further from said axis—to thereby lengthen the feeding movement of said bar and its feed dog. At its upper end the screw 70, Fig. 11, has a smooth cylindrical head portion which rotatably engages through an opening 72 in a cap plate 73 (Fig. 12), and has a nick therein for engagement of a screw driver. Said cap plate 73 is rigidly secured to the upper end of arm 41 of the feed rocker by means of a screw 74 and a rib 75 on the under surface of said cap plate fitting in a groove 76 across the upper end of said arm 41—see particularly Figs. 2, 3, 4, 5 and 10. The cap plate 73 thus provides a support for the upper end of adjusting screw 70 as well as a bearing in which said screw is rotatable.

At its lower end screw 70 has a smooth cylindrical stem portion 80 of smaller diameter extending through and rotatable in a sleeve 81, which latter extends through a vertical opening in the base portion 42 of a feed rocker and is secured therein by a screw 82, the inner end of which engages an opening 83 in said sleeve 81. A head 85, having a roughened peripheral gripping surface, is secured to the lower extremity of the stem portion 80 of the adjusting screw by a pin 86 engaging through registering openings in said head and stem portion—see Figs. 10 and 11. A nick across the end of stem portion 80, for engagement by a screw driver, registers with similar nicks across the head 85.

As will thus readily appear, to adjust the feeding movement of the front feed dog 27 relative to that of the rear feed dog 28, it

is only necessary to swing the bed plate upward on hinges (not shown) at its left-hand edge, Fig. 1, then grip the head 85 and turn the adjusting screw to shift the feed slide 65 and its pivotal connection 64 to feed bar 35, as may be desired. The desired adjustment may also be effected, without lifting the bed plate or cover by inserting a screw driver through an opening 90, Fig. 10, located in the cover over the adjusting screw, and engaging a screw driver in the nick at the upper end of the adjusting screw 70 and turning the latter as may be required. By such use of an adjusting screw and associated parts, finely drawn and accurate adjustments, impossible of attainment with feeding mechanisms such as ordinarily provided, may be made easily and quickly.

What is claimed as new is:—

1. The combination of a feed rocker having two arms, two feed bars positioned at one end between said arms and pivotally connected at said end to said arms respectively to be actuated thereby, and an adjusting screw for changing the position of the pivotal connection between one of said arms and its corresponding feed bar relative to the axis of oscillation of said feed rocker.

2. The combination of a feed rocker having two arms, two feed bars positioned at one end between said arms and pivotally connected at said end to said arms respectively to be actuated thereby, and an adjusting screw carried by said feed rocker and acting to change the position of the pivotal connection between one of said arms and its corresponding feed bar relative to the axis of oscillation of said feed rocker.

3. The combination of a feed rocker having two members radiating from the axis of oscillation of the rocker, two feed bars positioned at one end side by side between said members of the rocker, a pivot connecting said end of one of said bars to one of said members of the rocker, an adjustable pivot member connecting said end of the other of said bars to the other of said members of the rocker, said pivot member being movable in a guideway of said rocker member towards and from said axis of oscillation of the rocker, and an adjusting screw carried by said rocker and adapted to change the position of said adjustable pivot member in its said guideway.

In testimony whereof I have signed this specification.

REUBEN BALL THOMPSON.
